UNITED STATES PATENT OFFICE

2,238,148

SHAVER

Oswald F. Zahn, San Diego, Calif.

Application September 13, 1938, Serial No. 229,687

8 Claims. (Cl. 30—43)

My invention relates to shavers for shaving hair and the objects of my invention are:

First, to provide a shaver with vacuum means in connection therewith for drawing the skin and hair into cooperative relation with the shearing blade of the shaver so that an extremely close shave may be attained;

Second, to provide a vacuum operated means for causing a vacuum in connection with the shaver head and shaver blade for drawing the skin into curved form in close relation with the shaver blade and holding the same in said curved close relation while the shaving is effected;

Third, to provide a shaver head that is so shaped and constructed that a vacuum may be efficiently and effectively applied thereto for drawing the skin into close relation with the shaver blade during the shaving operation;

Fourth, to provide a shaver head and shaver blade and vacuum means in cooperative relation therewith that tend to raise the hair outwardly for close cutting while operating the shaver;

Fifth, to provide a shaver of this class in which the vacuum means may be utilized for the purpose of causing air pressure through the shaver in reverse direction for cleaning the blade and shaver head;

Sixth, to provide a novelly constructed shaver head;

Seventh, to provide a novelly constructed shaver blade; and

Eighth, to provide a shaver of this class which is very simple and economical of construction, easy to operate, easy to clean, efficient in its action and while will not readily deteriorate or get out of order.

With these and other objects in view as will appear hereinafter, my invention consists of certain novel features of construction, combination, and arrangement of parts and portions as will be hereinafter described in detail and particularly set forth in the appended claims, reference being had to the accompanying drawing and to the characters of reference thereon which form a part of this application in which:

Figure 1 is a side elevational view of my shaver showing the body and vacuum bulb tube fragmentarily; Fig. 2 is a bottom view of a fragmentary portion thereof; Fig. 3 is an enlarged fragmentary sectional view taken from the line 3—3 of Fig. 2 and showing some of the parts in elevation to facilitate the illustration; Fig. 4 is a fragmentary sectional view taken from the line 4—4 of Fig. 3 showing some of the parts in elevation to facilitate the illustration; and Fig. 5 is a diagrammatic view showing the application of the shaver head to the skin and hair with the application of the vacuum showing the relation of the hair with the skin before, during and after the shaver passing over the skin and the shape of

the skin relative to the shaver head during the shaving operation.

Similar characters of reference refer to similar parts and portions throughout the several views of the drawing:

The shaver head 1, shaver blade 2, drive shaft 3, journal member 4, vacuum bulb 5, and body member 6 constitute the principal parts and portions of my shaver.

The shaver head 1 is provided at its face engaging side with an elongated concavo-convex portion 1a, leaving side edge face engaging portions 1b and 1c, and end edge engaging portions 1d and 1e, all of said edges being on the same plane. This member 1 is relatively thin and provided with a plurality of holes 1f therethrough and extending upwardly and outwardly from these edges 1b to 1e inclusive are the side members 1g and 1h and end members 1i and 1j forming an upwardly tapered rectangular shaped upper end into which is secured the body member 6 as shown in Fig. 1 of the drawing, thus providing a hollow head member 1.

Communicating with the side member 1h is an extended tubular portion 1k over which is stretched the one end of a tube 5a which connects at its opposite ends with a bulb 5 which is hollow and without any openings therein so that all air passing in and out of the bulb 5 must pass through the openings 1f. Positioned on the elongated convex surface of the portion 1a of the shaver head 1 and reciprocally mounted longitudinally thereon is the shaver blade 2, which is provided with an elongated curved surface conforming to the convex surface of the portion 1a and adapted to reciprocate thereon in engagement with the portion 1a. This portion 2 is provided with a plurality of holes 2a therein conforming substantially with the holes 1f in the portion 1a. It is provided with a central lug 2b which is provided with a central recess 2c therein in which is mounted the eccentric end 3a of the drive shaft 3, the shaft being shown best eccentrically in Fig. 3 of the drawing. The lug 2b, it will be noted is elongated and has an elongated hole or slot 2c to permit the eccentric portion 3a of the shaft 3 to shift in said slot and reciprocate the blade member 2 longitudinally on the surface of the portion 1a of the shaver head 1. This shaft 3 may be connected with any power producing mechanism such as a motor, air compressor or the like for mechanically or electrically operating the blade 2, the motor not shown.

The shaft 3 is mounted in a journal member 4 which is provided with packing 4a to form a substantially tight joint around the shaft 3. This journal member 4 is supported by means of a partition 4b secured to the inner side walls of the shaver head 1 slightly above the tubular member 1k and forms an air tight partition in

said shaver head 1 and confines the air and vacuum in the small space below the partition 4b as shown best in Fig. 3 of the drawing.

The operation of my shaver is substantially as follows: Power is applied to the shaft 3 for revolving the same by any power producing mechanism. The bulb 5 is compressed in the hand of the operator and the shaver head is placed against the skin to be shaved, the edges 1b to 1c resting firmly against the skin. Then the bulb 5 is released and the skin is drawn into the concave side of the portion 1a and held therein while the shaver is moved over the surface of the skin and the blade 2 reciprocated over the portion 1a by the revolution of the shaft 3, the skin being drawn against the concave side of the member 1q and the hair drawn through the holes 1f and 2a where it is sheared by the reciprocation of the blade 2 over the portion 1a. In Fig. 5 is shown a diagrammatic view of the position of the skin during the shaving operation, the direction of the shaver movement being shown by the arrow in Fig. 5. It will be noted that the skin is drawn tightly in substantially convex outer surface form against the concave under surface of the portion 1a which tends to raise the hairs upwardly out of the skin as shown in Fig. 5 at the middle and they are cut off while in this projected position so that after the shaver has passed over, their ends are substantially below the surface of the skin as shown at the right in Fig. 5 of the drawing. It being noted that not only are the hairs raised outwardly as shown in Fig. 5 of the drawing, but at the same time as the hairs enter the cutting openings, they are drawn still farther out of the skin.

Though I have shown and described a particular construction, combination and arrangement of parts and portions, I do not wish to be limited to this particular construction, combination and arrangement, but desire to include in the scope of my invention, the construction, combination and arrangement substantially as set forth in the appended claims.

Having thus described my invention, what I claim as new and desire to secure by Letters Patent is:

1. In a shaver of the class described, the combination of a shaver head provided with an elongated concave portion with a substantially rectangular face engaging edge provided with hair receiving openings therein, all of which are spaced inwardly from said edge and said shaver head being wholly air tight surrounding said openings and edge and a shaver blade shiftably mounted in contact with the inner side of said concave portion.

2. In a shaver of the class described, the combination of a shaver head provided with an elongated concave portion with a substantially rectangular face engaging edge provided with hair receiving openings therein, all of which are spaced inwardly from said edge and said shaver head being wholly air tight surrounding said openings and edge, a shaver blade shiftably mounted in contact with the inner side of said concave portion, and expandable vacuum means independent of the operating means of said shaver communicating with the interior of said shaver head.

3. In a shaver of the class described, the combination of a shaver head provided with an elongated concave portion with a substantially rectangular face engaging edge provided with hair

receiving openings therein, all of which are spaced inwardly from said edge and said shaver head being wholly air tight surrounding said openings and edge, a shaver blade shiftably mounted in contact with the inner side of said concave portion, and vacuum means independent of the shaver operating mechanism communicating with the interior of the shaver head.

4. In a shaver of the class described, the combination of a shaver head provided with an elongated concave portion with a substantially rectangular face engaging edge provided with hair receiving openings therein, all of which are spaced inwardly from said edge and said shaver head being wholly air tight surrounding said openings and edge, a shaver blade shiftably mounted in contact with the inner side of said concave portion, said shaver head being entirely enclosed and air tight except for the hair receiving openings therein and expandable vacuum means operated independently of the shaver operating mechanism communicating with the interior of the enclosed portion of said shaver head.

5. In a shaver of the class described, the combination of a shaver head provided with an elongated concave portion with a substantially rectangular face engaging edge provided with hair receiving openings therein, all of which are spaced inwardly from said edge, said shaver head being wholly air tight surrounding said openings and edge, a shaver blade shiftably mounted in contact with the inner side of said concave portion, and a resilient vacuum bulb communicating with the interior of said shaver head, said resilient vacuum bulb being entirely closed except for its tube connection.

6. In a shaver of the class described, the combination of a shaver head provided with an elongated concave portion with a substantially rectangular face engaging edge, which face engaging edge is wholly on substantially the same plane, said concave portion provided with hair receiving openings therein, all of which are spaced inwardly from said edge and said shaver head being wholly air tight surrounding said openings and edge and a shaver blade shiftably mounted in contact with the inner side of said concave portion.

7. In a shaver of the class described, the combination of a shaver head provided with concave portion with a face engaging edge provided with hair receiving openings therein, all of which are spaced inwardly from said edge and said shaver head being wholly air tight surrounding said openings and edge, a shaver blade shiftably mounted in contact with the inner side of said concave portion, and expandable vacuum means independent of the operating means of said shaver communicating with the interior of said shaver head.

8. In a shaver of the class described, the combination of a shaver head provided with concave portion with a face engaging edge provided with hair receiving openings therein, all of which are spaced inwardly from said edge, said shaver head being wholly air tight surrounding said openings and edge, a shaver blade shiftably mounted in contact with the inner side of said concave portion, a resilient vacuum bulb communicating with the interior of said shaver head, said resilient vacuum bulb being entirely closed except for its tube connection.

OSWALD F. ZAHN.
